(57) **CLAIM**

The ornamental design for a power station, as shown and described.

DESCRIPTION

FIG. 1 is a perspective view of a power station showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a partial enlarged view of the encircled area "8" of FIG. 1; and,

FIG. 9 is a partial enlarged view of the encircled area "9" in FIG. 6.

The equal-length broken lines in the drawings depict portions of the power station that form no part of the claimed design. The dash-dot-dash broken lines define the boundaries of the claim.
